UNITED STATES PATENT OFFICE.

CYRUS W. RICE, OF PHILADELPHIA, PENNSYLVANIA.

WRENCH FOR OPERATING DROP-BOTTOM CARS.

1,113,248.

Specification of Letters Patent.

Patented Oct. 13, 1914.

Application filed February 1, 1913. Serial No. 745,556.

To all whom it may concern:

Be it known that I, CYRUS W. RICE, a citizen of the United States, residing at the city of Philadelphia, in the county of Philadelphia and State of Pennsylvania, have invented certain new and useful Improvements in Wrenches for Operating Drop-Bottom Cars, of which the following is a specification.

10 My invention relates to wrenches for operating steel or other drop bottom cars, to safely raise or lower the bottoms thereof; and in such connection it relates to the constructive arrangement of such wrench for 15 the defined purpose, among other uses therefor.

The nature and scope of my present invention will be more fully understood from the following description taken in connection 20 with the accompanying drawings forming part hereof, in which—

Figure 1, is an end elevational view of a wrench, embodying the main features of my invention. Fig. 2, is a view partly in central longitudinal section and partly in top plan of the wrench, showing the handle-bar having a recessed seat with its rear curved walls and sides in part offset; the rotary flanged reversible wrench-head and yoke 25 having a fork-like extension to movably engage the seat of the handle-bar to afford reciprocal movement of the yoke and wrench-head keyed thereto by a ratcheted surface wedge offset in one portion to enable a shiftable locking device of the handle-bar being brought into engagement in the operative relation of the wedge with the wrench-head; and Fig. 3, is a front elevation of a portion of the face of the wedge, 30 showing the particular formation thereof, engaging the surface of the wrench-head, as illustrated in Fig. 2.

Referring to the drawings *a*, is preferably a two-part handle-bar the two parts detachably fitting each other, as shown in Fig. 1, and provided with a recessed flat seat *a*¹, having curved rear walls *a*² and *a*³, on both sides, for a purpose to be presently fully explained.

50 The outer edges of the seat *a*¹, are provided with offsets *a*⁴ and *a*⁵. A shiftable locking device *b*, is provided, consisting of a metal strip *b*¹, having at the outer end a projection *b*², through which extends a screw-bolt *b*³, having a tightening-nut *b*⁴, to

engage and tighten said bolt in the offset *a*⁴ or *a*⁵, of the seat *a*¹, for a purpose to be presently explained.

A yoke *c*, is provided which has a fork-like extension *c*¹, to movably fit the seat *a*¹, and to be held by means of a headed bolt *c*², which forms the pivotal bearing for the yoke *c*, with the seat *a*¹, of the handle-bar *a*. The bolt *c*², is provided with an opening in one extremity *c*³, to insert a cotter-pin *c*⁴, 65 so that the yoke and seat may be held in a reciprocatory relation with each other.

A reversible flanged wrench-head *d*, is provided, which is recessed at *d*¹, in its periphery and with which engages an irregular-shaped ratcheted surface wedge *e*, as clearly shown in Fig. 3, having an offset *e*¹, and a ring *e*², the latter being provided so as to readily insert and withdraw the wedge to or from the space *e*⁵, of the yoke extension. The wedge in its operative locked position bears against the recessed surface *d*¹, of the wrench-head *d*, as shown in Fig. 1, and when so seated the screw-bolt *b*³, of the locking device *b*, is shoved into the offset *e*¹, of the wedge to prevent displacement of the same and while manipulating the wrench-head, under slight reciprocatory movement of the yoke *c*, on the seat of the handle-bar *a*, and the wrench-head is engaged with a square-shaped pivot extending from either side of a drop bottom car, for either raising or lowering the same.

It will be observed from Fig. 1, that the wrench-head is arranged so as to be readily reversed in its operative relation with the yoke *c*, for actuating the bottom from either the right side or the left side, to discharge its contents or to close the wings of said bottom.

By the foregoing arrangement of the wrench, the operator is protected against accidents during operation of the car bottom to discharge contents, because after releasing the dog controlling the turning bar or pivot holding the wings of the bottom to each other, the wrench-head is firmly held by the ratchet wedge until the said bar, frequently released suddenly by the weight contained above the bottom of the car and in direct bearing, reverses the wrench-head, which in turn releases the wedge and weight of the handle-bar against the wedge, thus giving free turning action to the wrench-head and the released turning bar held by 110

the wrench-head of the wrench, preventing serious accidents common to the general employment of solid wrenches for the purpose.

Having thus described the nature and objects of my invention, what I claim as new and desire to secure by Letters Patent is:—

In a wrench, a handle-bar provided with a recessed seat and curved walls, outer edges of said seat having offsets, a shiftable locking device having a projection through which extends tightening means, a yoke having a forked extension in reciprocating relation with said seat, a reversible flanged wrench-head, a ratcheted surface wedge having an offset and a ring, the latter being provided to insert and withdraw said wedge

to or from said yoke extension, said wedge in its operative locked position bearing against the recessed surface of said wrench-head and when so seated, the tightening means of said locking device is in relation with the offset of said wedge to thereby prevent displacement during manipulation of said wrench-head, substantially as described. 20

In witness whereof, I have hereunto set my signature in the presence of the two subscribing witnesses hereto. 25

CYRUS W. RICE.
